PORTABLE VAPOR BATH

Samuel J. Preston, Newark, N. J.

Application April 25, 1940, Serial No. 331,510

4 Claims. (Cl. 4—163)

This invention relates to improvements in portable vapor baths for administering vapor and warm air baths in the treatment of various diseases.

An object of this invention is to provide a pliable and collapsible tubular container having an opening at each end, one end of the container having means for securing same around a receptacle for a liquid, and the other end being adapted to closely encircle the neck of a patient.

Another object of this invention is to provide a receptacle in the lower end portion of the container, the receptacle being adapted for vaporizing a liquid and to provide superposed coarse and fine screens in said receptacle for reducing the wetness of the vapor.

Another object of this invention is to provide a portable vapor bath comprising a pliable and collapsible tubular container having an elongated opening therein extending substantially from end to end of the container, and having fastening means whereby the edges of the said opening may be released from each other, and may be intimately closed throughout its entire lineal extent.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference will designate corresponding parts throughout the several views, in which:

Figure 1 is a fragmentary perspective view of the portable vapor bath.

Figure 2 is a perspective view of the portable vapor bath as applied in connection with a cot, with the patient in lying position.

Figure 3 is a side elevation of the portable vapor bath with the patient in a sitting position.

In the illustrated embodiment of the invention shown in Figure 1, the numeral 10 indicates a portable vapor bath appliance comprising a tubular container 11 preferably made of pliable and collapsible materials such as oil silk, rubber, or other suitable material.

The appliance 10 includes a receptacle 12 for a liquid 13. A heating element 14 has been placed in the receptacle 12. The heating element 14 is preferably an electric heating pad having a resistance conductor connected by means of an electric cord 15 to an electric plug 16.

A control switch or rheostat 17 has been ar-

ranged in circuit with the electric cord 15 and acts as a controlling device for the electric circuit. The physician or patient adjusts the rheostat 17 to permit more or less current to pass through the heating element 14 to raise or lower the temperature as desired and to obviate the risk of overheating.

5 The receptacle 12 has a coarse screen 18 above the liquid 13. The screen 18 is preferably made of coarse wire mesh and serves to prevent large globules of hot liquid from passing upwardly.

10 The receptacle 12 also has a fine screen 19 in superposed relation with the coarse screen 18. The screen 19 is preferably made of fine wire 15 mesh of a size which will allow passage therethrough only of vapor. The screens 18 and 19 thus serve to reduce the wetness of the vapor entering the container 11.

15 The lower end portion 20 of the container 11 has been secured in circumscribing sealing relation around the container by means of a gasket 21 contacting the container surface and a circumscribing band or wire 22, the ends of which are knotted or otherwise suitably secured (not 25 shown).

A detachable arm 24 having a substantially T-shaped upper end 25 has slots 26, 26, shaped like key-holes at its lower end. The circular lower ends of the key-hole slots serve for receiving the 30 heads of screws 27, 27. The screws serve to attach the arm 25 solely and directly to the receptacle 12. The arm 25 prevents collapse of the tubular container and holds the container open so the vapor can travel freely upwardly.

35 An opening 28 has been formed in one side of the tubular container 11. The opening 28 is coextensive with the length of the container. A slide closure fastener means 29 commercially known as the "zipper" type has been applied to 40 the opening whereby the edges at said opening may be released from each other and for intimately closing said opening throughout its entire lineal extent.

The fastener means is of the usual construction 45 and is shown in the drawings only for the purpose of illustration, it being understood that any fastener means adapted to latch and form a metal seam that can be completely separated by the manipulation of a sliding body from end to end of the opening may be used.

The side of the container adjacent the rheostat 17 has a slit 30 through which the patient may extend his hand for operating the rheostat 17 so as to regulate the heat inside the container 11.

Figure 2 shows the portable appliance 10 used in conjunction with a patient lying on a cot 31. It will be noted that the vaporizing end portion 32 of the appliance has been elongated to make the container 11 fully collapsible to permit its passage between bedposts (not shown) and then attached to the receptacle 12.

Figure 3 shows the portable appliance 10 used in conjunction with a chair 33. It will be noted that the patient is inside the container 11, up to his neck and in sitting position. As shown in the drawings, the neck portion is much smaller than the body portion of the container or envelope, so as to fit around the neck of the patient.

As best shown in Figure 2, it is to be noted that the appliance disclosed herein makes it possible for a bed-ridden patient to be given a vapor bath while lying on the bed and without being raised therefrom. The appliance makes it possible to be placed flat on the bed with the elongated opening therein at one side of the patient and to roll the patient into the container 11 without raising any portion of the patient's body. The "zipper" is then closed and the electric current turned on.

In accordance with the patent statutes I have described and illustrated the preferred embodiment of my invention, but it will be understood that various changes and modifications can be made therein without departing from the spirit of the invention as defined by the appended claims.

I claim:

1. In an apparatus for treating disease, an elongated pliable and collapsible tubular envelope of a size adapted to inclose the entire body of a patient while exposing the head of the patient, said envelope being sufficiently pliable to permit being placed flat on a bed substantially throughout its entire length, a receptacle for a liquid positioned at the foot end of said envelope, means at the foot end portion of said envelope and being detachably secured to said receptacle for preventing said envelope from collapsing, the head end portion of said pliable envelope being adapted to fit the neck of the patient, said foot end portion having an opening, heating means for vaporizing a liquid and communicating with said opening in said foot end portion, said envelope having electric current regulating means secured thereto and having an opening permitting outward passage of an arm of a patient for adjusting said regulating means and the temperature within said envelope.

2. In a portable vapor bath for treating disease, an elongated pliable and collapsible tubular envelope having a lengthwise opening and being of a size adapted to inclose the entire body of a patient, said opening being of a length to be co-extensive with the length of said envelope, means for intimately and releasably closing said opening, said envelope being sufficiently pliable to permit being placed flat on a bed substantially throughout its entire length, a receptacle for a liquid positioned at the foot end of said envelope, means at the foot end portion of said envelope and being detachably secured to said receptacle

for preventing said envelope from collapsing, the head end portion of said pliable envelope being adapted to fit around the neck of the patient, said foot end portion having an aperture, means for vaporizing a liquid, and means for securing said foot end portion around said vaporizing means.

3. In a portable vapor bath for treating disease, an elongated pliable and collapsible tubular envelope having a lengthwise opening and being of a size adapted to inclose the entire body of a patient while exposing the head of the patient, said opening being of a length to be co-extensive with the length of said envelope, means for intimately and releasably closing said opening, said envelope being sufficiently pliable to permit placing said envelope flat on a bed substantially throughout its entire length, a receptacle for a liquid positioned at the foot end of said envelope, means at the foot end portion of said envelope and being detachably secured to said receptacle for preventing said envelope from collapsing, the head end portion of said pliable envelope being adapted to fit around the neck of the patient, said foot end portion having an aperture, means for vaporizing a liquid, means for removing excess moisture and conveying substantially dry vapor into said envelope, and means for securing said foot end portion around said vaporizing means, said envelope having electric current regulating means secured thereto and having an opening permitting outward passage of an arm of a patient for adjusting said regulating means and the temperature within said envelope.

4. In a portable vapor bath for treating disease, an elongated pliable and collapsible tubular envelope having a lengthwise opening and being of a size adapted to inclose the entire body of a patient while exposing the head of the patient, said opening being of a length co-extensive with the length of said envelope, means for intimately and releasably closing said opening, said envelope being sufficiently pliable to permit placing said envelope flat on a bed substantially throughout its entire length, a receptacle for a liquid positioned at the foot end of said envelope, means at the foot end portion of said envelope and being detachably secured to said receptacle for preventing said envelope from collapsing, the head end portion of said pliable envelope being adapted to fit the neck of the patient, said foot end portion having an aperture, means for vaporizing a liquid, means for removing excess moisture and conveying substantially dry vapor into said envelope, and means for securing said foot end portion to said vaporizing means, said envelope in said flat and open position on a bed being adapted for rolling a bedridden patient therein for vapor bath treatment, said envelope having electric current regulating means secured thereto and having an opening permitting outward passage of an arm of a patient for adjusting said regulating means and the temperature within said envelope.

SAMUEL J. PRESTON.
